DESIGN FOR A DRESS

Rose Hochberg, New York, N. Y.

Application December 17, 1937, Serial No. 73,672

Term of patent 3½ years

To all whom it may concern:

Be it known that I, Rose Hochberg, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The prints shown in parts, is continuous around the front and rear of the dress and sleeves.

The characteristic feature of my design resides in the combination on the specific two piece dress disclosed of a lace ruffle trim extending around the front peplum, along the front opening, and around the neckline, in association with the specific button trimmed ribbons on the blouse front, and the Shirred shoulders, as shown.

I claim:

The ornamental design for a dress, substantially as shown, and described.

ROSE HOCHBERG.
